UNITED STATES PATENT OFFICE.

WILLIAM J. WESSELER, OF EAST CLEVELAND, OHIO, ASSIGNOR OF ONE-HALF TO ALBERT H. FISHER, OF EAST CLEVELAND, OHIO, AND ONE-HALF TO DELBERT M. STAFFORD, OF CLEVELAND, OHIO.

WINDOW CONSTRUCTION.

Application filed April 26, 1927. Serial No. 186,684.

This invention as indicated relates to a window construction. More particularly said invention includes a frictional suspension for a window and means for controlling the same. 5 It also includes an interlocking relation between the window sash and the window frame whereby the support at one side of the window coats with the support on the opposite side of the window both with respect to movement in the plane of the window and transversely thereof with means for adjusting the degree of tension or pressure applied at either side of the window. It also has in view self-adjusting guide members which will automatically compensate for expansion or contraction of wooden window frames and sashes and present binding action or undue freedom of motion. It also contemplates dispensing with a parting strip and vertical stops in a 20 window construction, and includes features of construction incidental thereto.

To the accomplishment of the foregoing and related ends, said invention, then consists of the means hereinafter fully described and 25 particularly pointed out in the claims.

The annexed drawing and the following description set forth in detail certain mechanism embodying the invention, such disclosed means constituting, however, but several of various mechanical forms in which the principle of the invention may be used.

In said annexed drawing:

Fig. 1 is a front elevation showing a double window and window frame embodying the principle of my invention; Fig. 2 is a central vertical sectional view of the structure shown in Fig. 1; Fig. 3 is a horizontal sectional view through the upper and lower window sashes when in overlapped or opened position; Fig. 4 is a detail sectional view showing a resilient guide member and adjusting means therefor; Fig. 5 is a front view of the resilient guide member showing the adjusting slot therein; Fig. 6 is an enlarged detail view of the adjusting screw; Fig. 7 is a fragmentary front elevation showing a modified form of construction; Fig. 8 is an enlarged horizontal sectional view of a portion of the structure shown in Fig. 7; Fig. 9 is a 50 perspective view of an intermediate stop between the upper and lower window sashes; Fig. 10 is a fragmentary perspective view showing a stop block secured to the upper window sash; Fig. 11 is a fragmentary per-

spective view showing a stop block secured 55 to the upper edge of the lower window sash; and Fig. 12 is an enlarged horizontal sectional view showing the relation of the guide members and a pulley for the window cord.

As is clearly shown in Fig. 1 of the drawing, the window construction comprises a frame 1 which may be formed without vertical stops and with flat vertical faces against which resilient guide strips 2 preferably terminating in beaded edges 3 are adapted to be 60 secured. The guide strips have flattened portions 4 at their extreme edges which are secured by means of screws 5 or the like to the window casing. The strips are formed with an intermediate curved portion 6 which causes 65 said beaded portions to be spaced outwardly from said casing. An adjusting screw 7 is secured through said intermediate portion of said guide members, said screw preferably having a screw-threaded shank 8 and an enlarged head portion 9 between which is provided a narrow neck portion 10. The head is preferably polygonal in shape to permit adjustment of the screw by means of a wrench.

The threaded shank of the adjusting screw 80 is adapted to be received in an internally screw-threaded socket 11 embedded in the frame or casing. Opposite the position of the sockets, which are mounted at spaced points along the frame, each resilient guide 85 strip is provided with a slot 12. Each slot is formed with a narrow portion adapted to engage over the neck portion of the adjusting screw, and with an enlarged portion permitting the ready engagement of the adjusting screw with its socket when the parts are assembled. A shield (not shown) may be applied over open portion of the slot if it is desired to make the construction substantially water tight.

When the parts are engaged in operative position, the rotation of the screws in one direction will bring the inner shoulders adjacent the narrow neck portions against the resilient strip and force it outwardly, and rotation in the opposite direction will bring the outer shoulders into action and will positively move the resilient strip inwardly. Thus pressure or tension may be provided for the resilient guide member with reference to its action relative to its coacting guide member presently to be described.

The window sash, if of metal, is preferably

provided with grooved lateral edges and if of wood, is preferably channeled to receive a grooved metal guide plate. The grooved member in cross-sectional outline is preferably of more than semi-circumferential extent so that it may be engaged about said beaded edge of the resilient guide strip, heretofore described.

While a degree of friction sufficient to support a window in open position may be secured by having the area of contact of the grooved members and guide strips of large extent, it is desirable that the degree of friction be controlled. Where the device is applied to structures subjected to great vibration as ocean vessels, railroad cars, or motor vehicles, it would be desirable to use grooved members extending almost completely around the beaded members and apply a high degree of tension to the resilient guide strips so as to suspend the window firmly between spring members.

For certain installations such as those requiring the ready removal of the window, or an equivalent structure, such as a screen, the grooved member may be formed with a shallow groove not engaging about the beaded edge of the strip, but in such constructions adjustment of the friction must be provided for solely through control of the pressure of the resilient strips inwardly toward the window.

Where the construction is to be used in small boats, or in motor vehicles, or other instances, where a single window, or a single movable window sash is required only a single resilient guide strip need be provided at each side of the window, and the flat marginal portion of the guide strip may be secured to the outer or inner portion of the frame as desired. Where upper and lower movable window sashes are required, as in most dwellings and other buildings, the invention provides for the omission of the vertical stops and the parting strip now commonly used. Thus, as is shown in Fig. 2 of the drawing, the upper sash 21 is supported upon guide strips 22 secured to the frame outside of the plane of the window, and the lower sash 23 is supported upon guide strips 24, secured to the frame on the inside of the plane of the window. The upper frame member 25 of the upper sash is provided with a beveled face to contact with a like face on a stop 26 at the top of the frame, and the lower frame member 27 of the lower sash is likewise beveled to contact with a beveled stop 28 at the base of the frame. The other lower and upper frame members 31, 32, of the respective sashes are beveled, to coact with each other when the windows are in closed position. It will be noted that the resilient guide strips are slightly sprung apart as the beveled faces referred to are brought into contact and the windows held firmly in closed position.

In order to prevent air or moisture entering between the resilient guide strips, where the usual parting strip between the upper and lower sashes is dispensed with, an intermediate stop 33 is provided (see Fig. 9) between the resilient strips at each side of the frame at the meeting line of the upper and lower sashes. The stop is preferably a member formed with a flange 34 for securing the same to the frame and provided with channels 35, 36, on its upper and lower sides, adjacent its respective lateral edges. The channels are widened adjacent the flange 34 and are open at the narrower ends. Stop blocks 37, 38, secured respectively to the lower portion of the upper sash and the upper portion of the lower sash (see Figs. 10 and 11) and extend into the space between the resilient guide strips, the narrow neck portions 41, 42, of said blocks not interfering with the free sliding action of the window sashes on the guide strips. The stop block 37 is adapted to engage into the channel 36 of the intermediate stop and the stop block 38 with the channel 35. The contact faces 43, 44, of the stop blocks may be slightly beveled to coact with inclined surfaces 45, 46, of the respective channels.

The construction just described is intended to dispense with the use of counterweights and connecting members, the control of the friction of the guides serving to hold the window in any desired position. Where very heavy windows are to be equipped with resilient guides, it may be found desirable to provide counterweights and cables and pulleys. These may be concealed behind the resilient guide strips which are made of larger size. In such constructions the use of parting strips between the upper and lower sashes would also be desirable to facilitate making the construction weather tight. In the modified form of construction shown in Figs. 7 and 8, the lateral edge of the sash 51 carries a guide member 52 formed with a bead at its outer edge. A resilient strip 53 secured to the frame is folded upon itself to provide a groove 54 at its free edge and has a rearwardly projecting flange 55 providing a housing for the counterweight.

The counterweight 56 is supported on a cable 57 extending over a pulley 58 supported at the top of the guide strip on a pivot pin 59 supported in ears 61 integrally formed in said guide strip. The cable is positioned by said pulley centrally over the groove in the guide strip.

The resilient guide strip 53 is provided with adjusting screws 62 to control the tension or pressure upon the beaded guide member. In addition there is provided means for adjusting the friction of the groove upon the beaded guide. This comprises an adjusting screw 63 engaged in the rearwardly extending flange and passing through an aperture in the body portion of the resilient strip and controlled

by means of a thumb nut bearing against the body of said strip. Thus by means of said nut the clamping action of the grooved member may be controlled.

5 Other modes of applying the principle of my invention may be employed instead of the one explained, change being made as regards the mechanism herein disclosed, provided the means stated by any of the following claims 10 or the equivalent of such stated means be employed.

I therefore particularly point out and distinctly claim as my invention:

1. A device of the character described having in combination a window frame and a window sash, means provided on said window frame and said window sash for frictionally interengaging and interlocking to prevent lateral separation, and means operable in 20 either direction for adjusting the amount of such frictional engagement.

2. A device of the character described having in combination a window frame and a window sash, a pair of telescopically engaged 25 substantially tubular members supported respectively on said frame and sash, and means for controlling the degree of frictional engagement between said members by movement of one of them in either direction.

30 3. A device of the character described having in combination a window frame and a window sash, a pair of vertically disposed guide members, one of said members being secured to the frame and the other to the sash 35 of the window, and one of said guide members being adapted to clampingly engage over the other member and means for controlling the degree of clamping adjustment.

4. A device of the character described having in combination a window frame and a window sash, a pair of vertically disposed guide members, one of said members being secured to the frame and the other to the sash of the window, and one of said guide members 45 being adapted to clampingly engage over the other member, means for controlling the degree of clamping adjustment, and means for controlling the angular disposition of one of said guide members.

50 5. A device of the character described having in combination a window frame and a window sash, a pair of vertically disposed guide members, one of said members being secured to the frame and the other to the sash 55 of the window, and one of said guide members being adapted to clampingly engage over the other member, means for controlling the degree of clamping adjustment, and means for controlling the degree and direction of the resilient action of one of said guide members 60 with reference to its engagement with the other.

6. A device of the character described having in combination a window frame and a window sash, a guide member associated with

the sash of a window and a cooperating guide member associated with the frame of a window, said guide members each being substantially tubular members telescopically engaged with the other and a window cord adapted to 70 connect with the smaller tubular member while concealed within the larger tubular member.

7. A device of the character described having in combination a window frame and a window sash, a guide member associated with the frame of a window, said guide members each being tubular members telescopically engaged with the other and a window cord adapted to connect with the smaller tubular 80 member while concealed within the larger tubular member, and a pulley adjacent the upper end of said longitudinal member over which the cord extends.

8. A device of the character described having in combination a window frame and a window sash, a cylindrical guide member securely attached to the lateral edge of the window sash, a cooperating guide member resiliently supported upon the adjacent edge 90 of the window frame and engaging around said first-named guide member, and a flexible supporting cord concealed within said last named guide member and connected with said first-named guide member adjacent its upper 95 edge, a pulley secured adjacent the upper end of the guide member mounted on the sash and means provided behind said guide member for receiving the counterweight of said window.

9. A device of the character described having in combination a window frame and a window sash, a guide member of sheet metal resiliently supported adjacent one edge upon the frame and provided at its free edge with a 105 groove of slightly more than semi-circular cross-section and adapted to receive within the same a substantially cylindrical guide member secured to the window sash, means for controlling the frictional engagement of said curved guide member with said cylindrical guide member, and means for controlling the direction and extent of the resiliency of said resiliently supported guide member.

10. A device of the character described having in combination a window frame and a window sash, a guide member of sheet metal resiliently supported adjacent one edge upon the frame of a window and provided at its 120 free edge with a groove of slightly more than semi-circular cross-section and adapted to receive within the same a substantially cylindrical guide member secured to the window sash, means for controlling the frictional engagement of said curved guide member with said cylindrical guide member, and means for controlling the direction and extent of the resiliency of said resiliently supported guide member, a pulley adjacent the upper end of 125

said resilient guide member and a flexible cord extending over said pulley and adapted to extend within said groove to said cylindrical member and at its other end to extend 5 behind said resilient member for connection with a counterweight.

11. A device of the character described having in combination a window frame, a pair of window sashes movable longitudinally thereof, sealing elements positioned at the top and bottom of the frame respectively adjacent the line of movement of said upper and lower sashes respectively, coacting sealing elements formed on the upper and lower 15 sashes, resilient guide members for said sashes, said guide members permitting slight lateral displacement of the same as said sealing elements are brought into engagement.

12. A device of the character described having in combination a window frame, a pair of window sashes movable longitudinally thereof, a pair of beveled seats positioned at the top and bottom of the frame respectively adjacent the line of movement of said upper 25 and lower sashes respectively, coacting beveled faces formed at the top and lower edges of both the top and lower sashes, and resilient guide members for said sashes, said guide members permitting slight lateral displacement of said window sashes as they contact with said beveled faces.

13. A device of the character described having in combination a window frame, a pair of window sashes movable longitudinally thereof, a pair of beveled seats positioned at the top and bottom of the frame respectively adjacent the line of movement of said upper and lower sashes respectively, coacting beveled faces formed on the upper and lower 40 sashes, and resilient guide members for said sashes, said guide members permitting slight lateral displacement of said window sashes as they contact with said beveled faces, and means for controlling the degree of resiliency 45 of said guide members.

14. A device of the character described having in combination a window frame, a pair of window sashes movable longitudinally thereof, a pair of beveled seats positioned at the top and bottom of the frame respectively adjacent the line of movement of said upper and lower sashes respectively, coacting beveled faces formed at the top and lower edges of both the top and lower sashes, resilient guide members for said sashes, said guide members permitting slight lateral displacement of said window sashes as they contact with said beveled faces, and means for controlling the degree of resiliency of said guide members. 50 55 60

15. A guide member for a window formed of sheet metal bent to provide a resilient supporting section adjacent one edge and formed with a curved guide engaging member at its opposite edge, pulley wheel supports struck 65 up from the body portion of said guide member adjacent its upper end, a pulley wheel supported in said struck up support with the curved portion of said pulley wheel in alignment with the curved channel formed 70 at the free edge of said resilient member on one side and with a counterweight passageway on its opposite side.

16. A device of the character described having in combination a window frame, an 75 upper and lower sash movable longitudinally thereof, means at the lower corners of the upper sash and at the upper corners of the lower sash cooperating with adjacent parts to prevent entry of air through said structure. 80

17. A device of the character described having in combination a window frame, an upper and lower sash movable longitudinally thereof, means at the lower corners of the upper sash and at the upper corners of the lower sash cooperating with stationary members on the frame to close air passages through 85 said structure.

Signed by me this 7th day of April, 1927.
WILLIAM J. WESSELER.
